ELECTRONIC TIME CONTROLLED POWER
INITIATING MEANS

Maxwell P. Sparks, Chicago, Ill.

Application May 21, 1948, Serial No. 28,506

3 Claims. (Cl. 175—373)

1

The present invention relates to an electrical control means having an automatic timing means electrically connected to an electronic tube of the diode-tetrode type and a relay means for effecting the closing of a circuit operative to initiate the operation of a load, such as an automatic machine for playing records, whereby a selected and given record will be played at given instances or intervals of time.

Among the objects of the invention is to provide a novel means, as above referred to, for initiating the operation of a device, such as an automatic record player as mentioned above.

Another object of the invention is to provide such novel means with a timing means continuously operated by a synchronous motor with a cam-like means for given periods of time for closing a circuit to a diode-tetrode electronic tube connected in circuit or circuits to or with relay means affected from the tetrode side of the tube and by capacitance and resistance to effect a closing of a circuit to the means to be initiated in its operation, such means being generally called the load, and also for determining the time or duration of such operation initiation.

Other objects, capabilities, advantages and the like are comprehended by the invention as will later appear, and as are inherently possessed by the invention.

Referring briefly to the drawings:

Fig. 1 is a diagrammatic view of the invention;

Fig. 2 is a top plan view of the time control means forming part of the invention;

Fig. 3 is a side view of the same;

Fig. 4 is a diagrammatic view of the motor initiating circuit for operating the load;

Fig. 5 is a part section view of a load, such as a record player;

Fig. 6 is a top plan view of a switch means;

Fig. 7 is a side view of the means of Fig. 6; and

Fig. 8 is a view of a detail.

Referring more in detail to the drawings, the embodiment chosen to illustrate the invention comprises a casing 1, in which are housed elements later referred to and identified in the description of Fig. 5, and on which casing is mounted a time controlled power initiating device 2, a relay controlled switch 3 (see Figs. 6, 7 and 8), and also a tube 4, which may be of the diode-tetrode type.

The timing means 2 (see Figs. 2 and 3), comprises a base 5 operatively associated with and connected to a motor 6 of the synchronous type and having a shaft 7 extending up to and con-

2

nected with a timing disk or cam 8. To the base 5 is connected a chassis 9 for supporting a table 10 on which is supported a switch means 11, posts 12 and 13 for connection of conductors 14 and 15 running from a supply line, and also conductors 16 and 17 running to the motor 6 in the usual manner. The conductors 14 and 15 (see Fig. 1) are connected to a suitable connector 18, such as a plug-in means, for receiving current from the usual electrical line (not shown). These conductors 14 and 15 may have fuses 19 and 20 or the like, if desired.

The switch means 11 comprises a stationary contact element or means 23 supported on the table 10 by a suitable support 24 and this contact element or means 23 is connected to the post 12 by a conductor 21. (See Fig. 2.) Operatively associated with the stationary contact element 23 is a movable contact element or means 25 carried by a spring lever or arm 26 having its other end pivotally associated with a support 27 carried on the table 10.

On the support 27 is pivotally mounted an arm 28 which is connected to the spring lever 26 and at the free end of the arm 28 is provided a roller 29 adapted to normally ride on the periphery 30 of the cam disk 8 whereby the spring part 26 and the contact 25 will be held out (see dotted line position in Fig. 2) and the circuit is held open at the contacts 23 and 25. A spring 31 is connected to the arm 28 and to a stationary part 32 on the table 10, this spring normally urging the arm 28 and roller 29 inwardly against the edge or periphery 30 of the cam disk 8. The disk 8 has one or more notches or indentations 33, 33 in its periphery 30 so that as the disk 8 is rotated in given time angular movement, such as a quarter of an hour, a half hour, or the like, from notch to notch, as may be determined by the user, the roller 29 will be pulled by the spring 31 into the notch 33, whereby the spring switch member 26 will move inwardly to close the switch contacts 23 and 25 and thus close the circuit by way of the conductors 14 and 21, contacts 23 and 25, the switch part 26, and a conductor 22 leading to the tube 4. From the contact 13 runs another conductor 34.

Referring to Fig. 1 the tube 4 has filaments 35, 35 connected across conductors 22 and 34 by way of connectors 36 and 37. When the switch 26 is closed, these filaments are heated by the current from the line 14—15. Also current flows from the A. C. line 14 by way of conductor 21, switch 23—25—26 to conductor 22 by way of conductor 38, plate electrode 39 on the positive side of the

A. C. cycle to cause positive potential to be applied from the cathode 40 by way of the conductor 41 to a screen grid 42 of the tetrode side of the tube 4. In the tube 4 is also a plate 43 connected by conductor 44 to a relay coil 45 and thence by a conductor 46 to a grid 42, thus causing the positive potential to be applied to the plate 43 and causing the current to flow from the plate 43 through the conductors 44 and 46 and the relay coil 45, and causing the relay switches 47 and 48 to close. The relay switch 48 is connected by conductors 49 and 50 to the means to be initiated in operation, such as a selected record in a phonograph playing machine or the like. The relay 45 has a core 51 for causing the switches 47 and 48 to close.

When the switch 47 is closed, current flows from a battery 52 by way of the conductor 53 by way of the switch 47 thence to conductor 54 and thence to a resistor 55 and also charges a capacitor 56 to a terminal voltage of the battery 52. The conductor 54 is connected to the resistor 55 by way of conductors 57 and 58 and to a capacitor 56 by way of the conductors 57 and 59, and the resistor 55 and the capacitor 56 are connected to the conductor 34 by way of conductors 60 and 61 respectively. The conductor 57 runs to a grid 62 in the tube 4, and interposed between the grid 62 and the filament 35 is a cathode 63. Across the relay coil 45 is a capacitor 64 connected by conductors 65 and 66 respectively to the conductors 44 and 46.

The switches 47 and 48 of the switch means 3 are shown more in detail in Figs. 6, 7 and 8 and, as shown, comprise a base piece 67 supported on the member 1, and fixed to a bracket 68 which has an arm 69 upon which is carried an insulation block 70, which may be made up of laminations as desired and found convenient. The block 70 holds at an end thereof a plurality of resilient switch elements 71, 72, 73 and 74, and the forward ends 75 and 76 of elements 71 and 73 extend through a slot 77 in an upright arm 78 of an armature member 79 extending over the core 51 of the relay coil 45, and being pivotally supported or fulcrummed in the bracket 68 with a tail piece 80 connected to a spring 81 which is, in turn, connected to a base part of the bracket 68 (see Fig. 7). The elements 71 and 73 have contact points 82 and the elements 72 and 74 have opposed contact points 83 which are normally separated or open. The conductors 44 and 46 are connected to the relay coil 45 by way of posts 84 and 85 on the base member 67. The fixed ends of the spring elements 71 and 72 (see Figs. 6 and 7) are connected to the conductors 49 and 50, and the fixed ends of the spring elements 73 and 74 are connected to the conductors 53 and 54.

In the operation of this phase of the device, as current flows through the relay coil 45 the core 51 will attract the armature 79 to move the loop 78 down and hence the ends of the elements 71 and 73 also down to make the contacts 82 close contact with the contacts 83, and thus close the circuit of the conductors 49 and 50 to the load (not shown), the operation of which is to be initiated, and also close the circuit of the conductors 53 and 54 to the battery 52, resistor 55 and capacitor 56 (see Fig. 1).

In the operation of the device generally, the synchronous motor 6 constantly rotates the cam disk 8 whereon, in the main, the roller 29 rides on the periphery 30 of the disk 8, and when a

notch or indentation 33 moves to be opposite the roller 29, the spring 31 pulls the arm 28, from the dotted to the full line positions shown in Fig. 2, so that the roller 29 moves into the notch 33 and the switch member 26 with its contact 25 is moved into circuit closing contact with the contact 23. This closes the circuit whereby the current flows through the conductors 15 and 34, the filaments 35, conductors 36 and 22 through switch 23—25—23 and conductor 21 to the A. C. line 14. This action heats and lights the two filaments 35.

The current flows from the A. C. line 14 through the conductor 21 to switch 23—25—26, conductors 22 and 38, plate 39, on the positive half of the A. C. cycle and causes a positive potential to be applied from the cathode 40 through the conductor 41 to the grid 42 of the tetrode side of the tube 4. The plate 43 is connected by the conductor 44, relay coil 45 and conductor 46 to the grid 42. This causes positive potential to be applied to the plate 43 causing the current to flow from the plate 43 through the conductors 44 and 46 and the relay coil 45, thus causing the relay switches 47 and 48 to close. When the switch 47 is closed current flows from the battery 52 through the conductors 53, 54 and 57 to the resistor 55 and also charges the capacitor 56, and by way of the conductor 60, 61 and 34 to the terminal voltage of the battery 52. This voltage across the capacitor 56 causes the grid 62 to become so negative that the current flow through the tetrode side of the tube 4 ceases, causing the relay switches 47 and 48 to open again. It can be seen that the relay switches 47 and 48 remain closed for only a fraction of a second, as by way of example, a fifth of a second, or such other time as may be desired depending on the value of the parts used, such as the resistor 55 and the capacitor 56. The resistor 55 being connected parallel with the capacitor 56 is so large (approximately ten megohms) that the capacitor 56 (approximately forty microfarads) is not able to discharge in less than two minutes. This follows the formula; "time in seconds = the resistance $\times$ the capacitance." Meanwhile, this voltage across the capacitor 56 holds the tetrode side of the tube 4 in a non-conducting state. When the relay coil 45 is energized the switch 48 along with the switch 47 also closes and actuates the device to be controlled by way of the conductors 49 and 50.

The cam device of the motor 6 causes the switch 23—25—26 to remain closed for two minutes. The warm-up period of the tube 4 consumes thirty seconds of this time. The voltage held on the grid 62 causes the tube 4 to remain non-conducting for two or three minutes after the thirty seconds warm-up period. Meanwhile, two minutes after the switch 23—25—26 has closed, the cam 8 of the motor 6 causes the switch 23—25—26 to open again while the tube 4 is still non-conductive. Thus the relay closes the switches 47 and 48 only momentarily once per hour or one-half hour or whatever time for which the disk 8 is timed.

The device as disclosed is of especial use in connection with an automatic record player of known construction and shown in part in Fig. 5 as having a housing 86 provided with a table 87 supporting a post 88 above which is a tone arm 89 carrying a stylus or needle 90 for playing on a record 91, the arm 89 being connected to

the upper end of a shaft 92 operatively supported in the post 88.

Within the housing 86 is a number of record holders 93 capable of being selectively slid into place with a selected record in position for a turn-table 94 to pick up the record from its holder and bring it up to playing position with respect to the needle 90 and then return it to its tray or holder 93 upon descent of the turn-table 94. The turn-table 94 is carried at the upper end of a shaft 95 which is operatively associated at its lower end with suitable motor driven mechanism (not shown) for in proper time relation to carry the turn-table up and down and also to rotate it, in usual known manner.

The trays or holders 93 have suitable elements 96 by which selection of a tray or holder may be effected by suitable means carried by a shaft 97 suitably operated via a usual selecting device 98. The latter has a rotatable disk 99 beneath which is a plurality of solenoids 100 (see also Fig. 4) each having a core key 101 adapted when a selected coil 100 is energized to raise the key 101 into interfering position with a stop member or pin 102 carried by the disk 99. The conductors 49 and 50 run to a control board 103 forming part of the usual mechanism of the record player, shown in part in Fig. 5, and from this board the line 50 continues by way of a conductor 104 (see Fig. 4) to a coil 100 which when energized will raise the key 101 for its upper end 105 to be in the path of travel of the stop pin 102. The raising of the key 101 will bring the contact 106 carried by the key 101, in circuit closing contact with the point 107 of a conductor 108 running to the motor 109 of the record playing mechanism. From the coil 100 runs a conductor 110 to the secondary 111 of a transformer 112 and thence by a conductor 113 to the conductor 49 of the switch means 3, or more particularly the contacts 48 of that switch means.

Connected to the usual electric power line is a plug-in 114 in circuit with the primary 115 by way of the conductors 116 and 117. From the contact 106 runs a conductor 118 to the conductor 117, and from the motor 109 runs a conductor 119 to the conductor 116.

When the switch 48 is closed, the current impulse passes by way of the conductor 50 to the means 103, conductor 104 to coil 100, conductor 110 to secondary coil 111, and conductor 113 to conductor 49 of the switch 48. This effects a closing of the contacts 106 and 107 whereby current from the line plug 114 passes by way of the conductors 116 and 119 to the motor 109, thence by way of the conductor 108, contacts 107 and 106, conductors 118 and 117 to the plug 114. This initiates the operation of the record player and the selected record controlled by the particular coil 100 and key 101 is played in the usual way in the record player. The motor 109 operates appropriately the usual means for bringing the record in place in the path of the turn-table 94 which will lift the record to playing position against the needle or stylus 90 and after completing its playing the tone arm 89 shall have been moved to a position to cause the usual mechanism controlled and operated by the motor 109 to cause the turn-table to descend, leave the record on its tray 93, and then restore the tray 93 with its record 91 in stored position, after which the motor may stop or effect playing of another record that might have been chosen in a way peculiar to the record playing device.

While I have herein described and upon the

drawings shown an embodiment of the invention by way of illustration thereof, it is to be understood that the invention comprehends other constructions, details, arrangements of parts, features, and the like without departing from the spirit of the invention.

Having thus disclosed the invention, I claim:

1. An electronic time controlled power initiating means comprising a load circuit to be controlled, terminals adapted to be connected to a source of current for said power initiating means, relay means for controlling said load circuit, electronic means including anode, cathode, and grid means for controlling said relay means, cyclically operative means for periodically completing a circuit from said terminals to the anode-cathode circuit of said electronic means, a capacitor connected across said cathode and grid means for controlling the flow of current through said electronic means, means controlled by said relay means for effecting charging of said capacitor to put a negative charge on said grid means when said electronic means is conducting, impedance means having appreciable resistance for discharging said capacitor when said electronic means is non-conducting, and means responsive to application of current to said electronic means for causing energization of said relay means.

2. An electronic time controlled power initiating means comprising a load circuit to be controlled, terminals adapted to be connected to a source of current for said power initiating means, relay means for controlling said load circuit, electronic means including anode, cathode, and grid means for controlling said relay means, cyclically operative means for periodically completing a circuit from said terminals to the anode-cathode circuit of said electronic means, a capacitor connected across said cathode and grid means for controlling the flow of current through said electronic means, means controlled by said relay means for effecting charging of said capacitor to put a negative charge on said grid means when said electronic means is conducting, impedance means having appreciable resistance for discharging said capacitor when said electronic means is non-conducting, the values of said capacitor and said impedance means being so chosen that said electronic means can only become conducting once during each period of completion of the circuit from said terminals to said anode-cathode circuit by said cyclically operative means, and means responsive to application of current to said electronic means for causing energization of said relay means.

3. The combination set forth in claim 1 wherein the electronic means comprises tubes of the heater type having a time delay characteristic which supplements the delay characteristic of the capacitor during its charging period.
